UNITED STATES PATENT OFFICE.

JACOB HOUSHOLDER, OF BIG CHIMNEY, AND JOHN C. GALBREATH, OF CHARLESTON, WEST VIRGINIA.

CAR-COUPING.

No. 820,871.

Specification of Letters Patent.

Patented May 15, 1906.

Application filed July 24, 1905. Serial No. 271,012.

To all whom it may concern:

Be it known that we, JACOB HOUSHOLDER, a resident of Big Chimney, and JOHN C. GALBREATH, a resident of Charleston, in the 5 county of Kanawha, State of West Virginia, citizens of the United States, have invented a new and Improved Car-Coupler, of which the following is a full, clear, and exact description.

10 The invention relates to a car-coupler designed especially for use in connection with mine-cars.

The principal objects of the invention are to provide a simple automatic coupler of such 15 construction as will admit of dispensing with the usual draw-bar-and-link coupling and allow the coupling to be effected on curves equally as well as on straight lines.

The invention resides in certain novel features of construction and arrangement of parts, all of which will be fully set forth hereinafter and particularly pointed out in the 20 claims.

Reference is had to the accompanying 25 drawings, which illustrate as an example the preferred embodiment of our invention, in which drawings

Figure 1 is a plan view of the invention. Fig. 2 is a longitudinal section, and Fig. 3 is a 30 cross-section on the line 3 3 of Fig. 2.

10 indicates the buffer-beams of the mine cars or wagons or other vehicles to which the coupling may be applied. The coupling comprises male and female sections attached, 35 respectively, to the cars.

The male section of the coupling comprises a body formed of an essentially U-shaped bracket 11, embracing the buffer 10 and fastened thereto by bolts or otherwise. Projecting 40 from the bracket 11 are two lugs 12, between which the coupling-bar 14 is pivoted to swing freely in a vertical plane. The coupling-bar 14 has at its free end an upwardly-projecting stud 15, adapted to lock 45 with the female section of the coupler, as will hereinafter fully appear. The male member is provided with a clevis 16, attached to the pin 17, on which the before-mentioned coupling-bar is also mounted. The clevis is intended 50 to be used when hauling the car by mule-power.

The female section comprises a bracket 18, similar to the bracket 11 and bolted in place on the buffer-beam, as shown. Projecting

from the bracket is a socket-piece 19, having 55 an inwardly-facing internal shoulder 20 on its top wall and outwardly-flaring side walls 21, while the bottom wall is shortened to form an opening 22, as best shown in Fig. 2. Mounted in the socket-piece 19 to rock 60 around a horizontal pin 23 is an elbow-shaped latch, the long horizontal arm 24 of which projects forwardly over the opening 22 and the vertical arm 25 of which projects upwardly into proximity to the top wall of the 65 socket-piece. The arm 25 has in its upper end a notch 26, the purpose of which will hereinafter appear.

As shown best in Fig. 3, the top wall of the socket-piece has an opening 27 formed there- 70 in, and this opening is spanned by a key-plate 28. This opening receives a bolt 29, which has an opening 30 therein, receiving the key-plate 28. In this way the bolt is mounted to have limited vertical movement 75 in the top of the socket-piece. When the bolt is in its lower position, it engages in the notch 26 of the elbow-shaped latch and holds the latch with its horizontal arm 24 elevated, as shown in Fig. 2, and when the bolt is lift- 80 ed the latch drops, as indicated by the dotted lines in said view. When the latch is in its first position, its arm 24 holds the coupling-bar 14 raised with its stud 15 engaged with the shoulder 20, and the sections of the 85 coupling are thus engaged. By lifting the bolt 29 the latch is allowed to drop, and the stud 15 may then disengage the shoulder 20, allowing the coupling-sections to separate.

31 indicates a clevis for the same purpose as 90 the clevis 16. The clevis 31 is mounted on the pin 23, carrying the latch 24 25.

In the use of the invention, assuming the parts to be in the position shown in Fig. 2, it is only necessary to lift the bolt 29, thus drop- 95 ping the latch and releasing the coupling-bar, the bolt then resting on top of the arm 25 of the latch and the latch remaining in the lower position, (indicated by the broken lines in Fig. 2.) To recouple the cars, they should 100 be moved together, the coupling-bar entering the socket-piece and riding upon the lower or horizontal arm of the latch until the vertical arm of the latch is engaged by the coupling-bar, whereupon the latch is re- 105 turned to the position shown in Fig. 2, and the coupling-bar is elevated to engage its stud 15 with the shoulder 20 of the socket-

piece. At this time the bolt 29 drops and reenters the notch 26, engaging the shoulder formed thereby and locking the parts together. Owing to the flaring walls 21 of the 5 socket-piece, the coupling may be effected with equal facility on curves and straight lengths of track and said flaring walls also allowed to swing around curves without interfering with the engagement between the 10 two sections of the coupling.

Having thus described the preferred form of our invention, what we claim as new, and desire to secure by Letters Patent, is—

1. A car-coupling comprising a coupling 15 bar having a stud, a socket-piece having an interior shoulder for engaging the stud, positively-acting means for engaging the bar and lifting it into engagement with the shoulder, and means whereby the bar may actuate said 20 lifting means.

2. A car-coupling comprising a coupling 25 bar having a stud, a socket-piece having an interior shoulder for engaging the stud, means for engaging the bar and lifting it into engagement with the shoulder, means whereby the bar may actuate said lifting means, and means for locking said lifting means.

3. A car-coupling comprising a coupling 30 bar, a socket-piece, means within the socket-piece for retaining the coupling-bar therein, means for guiding the bar into engagement with said retaining means, means whereby the bar may operate said guiding means, and means for locking the guiding means.

35 4. A car-coupling comprising a coupling bar and a socket-piece, means on the bar for engaging the socket-piece, positively-acting means within the socket for lifting the bar into engagement with said means, and means

whereby the bar may operate said lifting 40 means.

5. In a car-coupling, the combination of a coupling-bar having a stud therein, a socket-piece having a shoulder adapted to be engaged by said stud, an essentially elbow-shaped latch mounted on the socket-piece and coacting with the coupler-bar, and a bolt for removably holding the latch in active position.

6. A car-coupling comprising a coupling 50 bar, a socket-piece having an interior shoulder adapted to be engaged by a part of the coupling-bar, an essentially elbow - shaped latch mounted in the socket-piece and coacting with the coupling-bar, and a bolt for removably holding the latch in place.

7. In a coupling, the combination of a coupling-bar, a socket-piece adapted to receive the same, an essentially elbow-shaped latch mounted in the socket-piece, one arm 60 engaging the coupling-bar to hold it in active position, and a bolt movable in the socket-piece and engaging the other arm of the latch removably to hold the same.

8. A car-coupling comprising sections hav- 65 ing coacting coupling devices, and clevises attached respectively to the sections and adapted to permit the connection of a team with the car through the medium of the coupling-section.

In testimony whereof we have signed our names to this specification in the presence of two subscribing witnesses.

JACOB HOUSHOLDER.
JOHN C. GALBREATH.
